UNITED STATES PATENT OFFICE.

JOHN POUNTNEY UDAL, OF BIRMINGHAM, ENGLAND.

DISPLAY OR ADVERTISING DEVICE.

Application filed October 27, 1927, Serial No. 229,184, and in Great Britain November 2, 1926.

This invention has for its object to provide an improved display or advertising device adapted for use in shop windows, on the exterior of buildings, or in any other desired position.

Referring to the three accompanying sheets of explanatory drawings:—

Figure 1 is an elevation with parts broken away showing in the upper half the front, and in the lower half the interior, one example of advertising devices constructed in accordance with this invention.

Figure 2 is a half sectional plan and Figure 3 is a cross section of the device.

Fig. 4 is a front elevation of the complete device.

Figure 5 is a front elevation with the lower half partially broken away.

Figure 6 is a cross section and Figure 7 a half sectional plan showing an alternative advertising device constructed in accordance with this invention.

Within the case *a* of the device are mounted a pair of horizontal bars *b* on which are slidably mounted a number of cross pieces *c* to the front of which are secured tablets *d* bearing the matter to be displayed. Five tablets are shown and the centre one may be fixed, the others being movable so that adjacent ones can be caused to overlap or to be extended. The two end cross pieces are connected by a horizontal bar *e*, and the intermediate ones by a like bar *f*. On each pair of bars *e*, *f*, are secured a pair of abutments *g*, *h*, respectively carrying rollers *i*, *j*.

The rollers *i* of the abutment *g* are acted on by opposite portions of a cam *k*, whilst the rollers *j* of the abutments *h* are acted on by the opposite portions of a cam *l* of different size. Both cams are secured to a spindle *m* which is rotated through a wheel *n* and pinion *o* from a shaft *p*. The latter may be driven by a pulley *q* or by any other suitable means.

It will be apparent that while the left hand tablets are in extended order, the right hand tablets overlap. Consequently the whole of the announcement conveyed by the tablets is not in view at any instant. The whole of the announcement is only seen by following the movements of the tablets from left to right, and during this movement, whilst the left hand tablets are moving the one behind

the other, the right hand tablets are becoming extended as indicated in Fig. 4.

In the alternative or modified construction shown in Figures 5 to 7, there is mounted in the frame *a* a pair of guide bars *b* on which can slide a pair of cross bars *c* which are connected together by tie bars *e*. Each cross bar is fitted with an abutment roller *i* which co-operates with a single cam *k*. The latter is mounted on a spindle *m* driven by a gear wheel *n*, a pinion *o*, and spindle *p* from a pulley *q*. To the front of the cross bar *c* is secured a single tablet *d* on which rows of printed or other matter may be depicted. This tablet lies behind of and is moved relatively to a plurality of fixed cross bars *r* on the front of the frame, which cross bars *r* may also have printed or other matter depicted thereon. The arrangement is such that during the reciprocation of the tablet *d* relatively to the cross bars *r* the matter to be displayed is moved progressively into and out of the proper position. Thus the verbal announcement may be brought into view progressively or may appear as a whole for only a short interval of time, or the combination of parts *d* and *r* may display a picture which is broken up at certain intervals and appears complete at other intervals.

Having thus described my invention what I claim as new and desire to secure by Letters Patent is:—

1. A display or advertising apparatus comprising a fixed frame, fixed and slidable tablets within the frame, bars carrying the slidable tablet or tablets, a pair of parallel guide rods on which the said bars can slide, cam mechanism situated between the said bars, and means for rotating the cam mechanism, substantially as described.

2. A display or advertising apparatus comprising a fixed frame, fixed and slidable tablets within the frame, bars carrying the slidable tablets, a pair of parallel guide rods on which the said bars can slide, cam mechanism situated between the said bars, means for rotating the cam mechanism, and means for rigidly connecting the slidable tablets in pairs, substantially as described.

In testimony whereof I have signed my name to this specification.

JOHN POUNTNEY UDAL.
